United States Patent Office.

HENRY GANNEY, OF LOUISVILLE, KENTUCKY.

Letters Patent No. 77,028, dated April 21, 1868.

IMPROVEMENT IN WATCH-KEYS.

The Schedule referred to in these Letters Patent and making part of the same.

TO ALL WHOM IT MAY CONCERN:

Be it known that I, HENRY GANNEY, of Louisville, in the county of Jefferson, and State of Kentucky, have invented a new and useful Improvement in "Watch-Keys;" and I do hereby declare that the following is a full, clear, and exact description thereof, which will enable those skilled in the art to make and use the same, reference being had to the accompanying drawings, forming part of this specification.

The improvement in watch-keys embraced in the present invention is of such a nature as to obviate all possibility of winding the watch-movement in the wrong direction, as well also as to prevent the watch from being over-wound, which is liable not only to break or snap the watch-spring, but also to injure the watch-movement in other respects.

In the accompanying plate of drawings my improvement in watch-keys is illustrated—

Figure 1 being a side view of a key made according thereto, and

Figure 2 a transverse section, taken in the plane of the line $x x$, fig. 1.

A, in the drawings, represents the spindle of the watch-key, which, at one end, B, is suitably bored out to fit over the axis of the main-spring of the watch-movement, and at its other, C, loosely passes through and turns in the frame or head-piece D of the key.

E, a spring, secured across one side of the head-piece D, on which it extends in a direction corresponding with the length of the spindle A, the spring being fixed at one end, a , but loose at its other, b , so as to slide or give upon the head-piece or frame D in a direction across the plane of the key-spindle A.

$a c$, two pins or studs, secured in key-spindle A, one upon each side of the same, in suitable position to abut against the spring E if the spindle is turned in the proper direction therefor.

From the above description of my improved watch-key, it is plain to be understood that, by turning the head-piece or frame D, the spindle A will be turned in conjunction therewith by the abutment of the spring attached to such frame against one of the pins a in the spindle, thus winding up the watch-movement so long as the force exerted by the key does not exceed the tension of the said spring, the said head-piece, the moment such force exceeds the tension of the spring, passing by the stud of the spindle on which it then loosely turns, thus releasing the watch-spring from all strain, and preventing all possibility of over-winding it, as is manifest.

A watch-key constructed as above described also obviates all possibility of winding the watch in the wrong direction—another important advantage.

I claim as new; and desire to secure by Letters Patent—

The combination of the head-piece D with its spring, E, spindle A, having one or more studs C, substantially as and for the purpose described.
